UNITED STATES PATENT OFFICE

2,522,901

ADJUSTABLE PICTURE HANGER

Sidney H. Schrager and Roy L. McGuire, San Francisco, Calif.; said McGuire assignor to said Schrager

Application October 30, 1948, Serial No. 57,546

2 Claims. (Cl. 248—31)

1

Our invention relates broadly to suspension type supports and more particularly to a picture or mirror hanging device by which vertical adjustments may be made to the end that a picture or mirror or other like device may be perfectly leveled while suspended upon a wall.

An object of our invention is to provide a new and novel form of suspension support which is particularly suitable for the hanging of pictures, heavy mirrors and like devices upon a vertical wall.

Another object of the invention is to provide a picture hanging support of a type which when used in pairs may be individually adjusted to provide for a leveling of a picture or other device supported thereby.

Other objects and advantages of our invention will be in part evident to those skilled in the art and in part pointed out in connection with the accompanying drawing, wherein there is shown by way of illustration and not of limitation a preferred embodiment of the invention.

In the drawing:

Figure 1 is a fragmentary view with one of our improved supports shown in section,

Figure 2 is a view similar to Figure 1 illustrating the manner in which our support may be manipulated to facilitate its attachment to loop of conventional design attached to the frame of a picture, or the like,

Figure 3 is a front view of our support, as shown in Figure 1, and looking to the left with the mirror removed,

Figures 4, 5 and 6 are views showing details of parts of our support.

We are aware that others have provided suspension means for supporting pictures and the like in which means are provided for adjustment, but so far as we have been able to determine none of these prior devices provide a means by which an adjustment may be made, to effect a leveling of a picture or mirror, without demounting or disconnecting the picture or other article suspended thereupon and while the weight of the picture or mirror is carried thereby. To meet this condition we provide a support which may be adjusted while supporting the weight of a picture or the like. This we accomplish by providing a saddle-like member that is adapted to be firmly secured upon a wall or a similar surface and from which there is suspended a threaded member that may be freely turned to control the elevation of a hook carried thereby upon which the article being supported is hung.

For a better understanding of our invention

2

reference is now made to Figures 1 and 2 of the drawing, wherein we have illustrated the preferred embodiment of our support. As here shown our support comprises a saddle member 10 that is adapted to be secured flat against a wall 11 in a conventional manner by two horizontally spaced and diagonally extending nails 12. This saddle member 10 has an outwardly extending flange 13 that has a centrally disposed hole through which a threaded member or machine screw 14 is projected downwardly so as to be suspended by its head and extending downwardly along its outer edge this flange 13 has a reinforcing lip 15. Slidably mounted upon the threaded member or screw 14 there is a hook member 16 that has a horizontally extending flange 17 at its upper end and a turned out hook forming portion 18 at its lower end. The flange portion 17 of the hook member 16 likewise has a centrally disposed hole through which the threaded member or screw 14 is adapted to extend and threaded upon the screw 14 there is a nut 19. This nut 19 is preferably of square outline and is of a dimension which will prevent its turning, as here shown, when assembled with respect to the hook-like member 16. In the drawing the hook member 16 is shown as adapted to engage with a clip or loop carrying plate 20 such as is customarily provided upon the backs of pictures, mirrors and like articles. It will be understood, however, that this hook forming portion 18 may take many forms depending upon the nature of its attachment to the picture and therefore this clip or loop carrying plate 20 forms no part of our present invention.

In connection with the above described assembly, it should be pointed out that the suspension screw accommodating hole in the saddle member 10 is made slightly larger than the shank of this member so that it may swing freely with respect thereto. Likewise the hole in the flange 17 of the hook-like member 16 is also made sufficiently large to permit a swinging of this member with respect to the screw 14. This will permit a manipulation of the assembled parts in the manner illustrated in Figure 2 of the drawing and thus facilitate an interconnection between the hook member 16 and the clip or loop carrying member 20 carried by the picture, here designated by the numeral 21.

By now referring to Figure 3 of the drawing it will be seen that when the parts are assembled as described above, the threaded member or screw 14 will be suspended from the saddle member 10 centrally between the two nails 12 by which the

saddle member is secured to the wall 11. As a result of this arrangement the load carried by the hook member 16 will be equalized between the two nails. If it should happen that the spacing between the saddle members 10 when fixed upon the wall 11 does not correspond exactly with the spacings between the clips or loop carrying plates 20 upon the picture or mirror the threaded member or screws 14 will be free to cant side-wise one way or the other so as to compensate for any such slight differences in alignment. The clip or loop carrying plate 20 is here shown in the form of a flat strip of metal which is adapted to be secured to a frame of picture or mirror by three screws 21 and is offset at its upper end and provided with a slot 22 through which the hook portion 18 of the hook member 16 may pass.

As is more clearly shown in Figure 4 of the drawing the hole in the flange 13 of the saddle member 10 is slightly elongated or in the form of a slot so that the threaded member or screw 14 may swing outwardly, as indicated in Figure 2, and to accommodate this outward swinging of the threaded member or screw 14 the lip 15 is notched out as at 23. In this figure of the drawing it will also be noted that the holes through which the nails 12 are projected are arranged in offset relation so as to provide for the diagonal disposition of the nails 12.

As illustrated in Figures 5 and 6 of the drawing the hook member 16 is capable of taking different shapes. For example, the hook shown in Figure 5, is primarily intended for use with clips or loop carrying plates such as the member 20 above described which are generally provided upon the backs of larger pictures and mirrors. As distinguished from this, in Figure 6, the hook forming portion 18 is shown as curved in two planes at its bottom to form a saddle-like configuration as at 24. This latter form of hook member will be found particularly suitable for use with eyelets such as are also provided for the hanging of pictures and the like. As a further variation it is conceivable that this hook forming member 16 may be formed from a length of wire with a right angled eyelet at its upper end through which the threaded member 14 will extend to engage the nut 19.

With the above described arrangement it will be seen that after the picture or mirror 21 has been hung upon the wall 11, as illustrated in Figure 1 of the drawing, the supports may be independently adjusted by a simple turning of one or the other of the threaded members or machine screws 14 with a screw driver, here designated by the numeral 25. In this manner a microscopic adjustment may be conveniently and effectively accomplished without any demounting of the picture.

While we have, for the sake of clearness and in order to disclose the invention so that the

same can be readily understood, described and illustrated specific devices and arrangements, we desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described our invention, what we claim and desire to secure by Letters Patent is:

1. In an adjustable hanger for pictures and the like, the combination of a saddle member adapted to be fixedly attached to the surface of a wall and having an aperture through which a threaded member may be projected, a threaded member extending through said aperture and depending from said saddle member, a movable hook member having a wall engaging portion and an offset flange with an aperture through which the depending end of said threaded member is extended, and a threaded nut at the outer end of said threaded member arranged and adapted to be held against turning by said hook member when said threaded member is turned, whereby the elevation of a picture suspended upon said hook member may be adjusted by a turning of said threaded member.
2. In an adjustable hanger for pictures and the like, the combination of a saddle member having spaced parallel portions with holes arranged diagonally in alignment through which nails may be driven to secure said member upon a wall, said saddle member having an aperture through which a threaded member may be projected and suspended, a hook member adapted to engage with the wall surface having an offset portion with an aperture in align with the aperture in said saddle member, a threaded member having an enlarged end by which it is suspended from said saddle member, and a nut upon the depending end of said threaded member arranged and adapted to be held against turning by said hook member when said threaded member is turned, whereby the elevation of said hook member with respect to said saddle member may be adjusted while carrying the weight of a picture or the like.
